UNITED STATES PATENT OFFICE.

WILFRED H. GEIS AND JAY EMERY VAN GUNDY, OF LOS ANGELES, CALIFORNIA.

DEPTHOMETER.

Application filed December 6, 1927. Serial No. 238,037.

This invention relates to a device for measuring accurately the depth of a hole, such as a well hole being drilled by a rig, such as a portable, standard or rotary drilling outfit, 5 wherein there is a line, a rope or wire cable, passing over a pulley or sheave, the line being run into the hole or used for the purpose of supporting and operating apparatus such as traveling blocks, casing, pipe, drill pipe, 10 tools, and the like which is run into the hole.

Well drilling outfits commonly used include a derrick or mast, at the top of which is a crown pulley or sheave or a set of such sheaves supporting apparatus to be run in 15 the hole. The line or cable is passed over such sheave or sheaves and, therefore, its travel bears a fixed ratio to the revolutions of the sheaves, as well as to the upward and downward motion of the traveling block, 20 the casing, pipe, tools, and such other things as may be used in the drilling of a hole.

The primary object of this invention is to provide a means to be used in well drilling for measuring exactly at all times the depth at 25 which the work is being performed in the hole, of running in, measuring in, and setting at desired depths, such apparatus or appliances as continuous strings of casing from the surface, packers or liners that may be 30 set at any predetermined position in the hole, to measure in the drill pipe as it is run in the hole for the purpose of drilling additional footage or of running in any other kind of tool or any manner of pipe; to locate accurately 35 the position of lost tools or "fish" or the place for reaming and like operations; and for determining the position at which certain strata of rock or changes in the character of the rock drilled may be encountered. 40 Another object of this invention is to provide such a measuring device which will accumulate and record both the one-way movement of the line, or the one-way movement of the traveling block, which supports the apparatus being run into the well, or will record 45 the total movement in one direction, subtracting any travel in the direction opposite to that being measured. A further object of this invention is to provide, in connection

with a rotary table, apparatus of the character described, in which a computing mechanism will be placed in inoperative position upon a load being placed upon the rotary table. A still further object of this invention is to provide an apparatus of the character last described, with means to retain the computing mechanism in operative condition during the time the rotary is being driven. 55

Other objects and advantages will be made fully apparent from the following specification considered in connection with the accompanying drawing, in which:

Fig. 1 is a front elevation showing the top of a derrick with a crown block assembly for rotary drilling; Fig. 2 is a side elevation of a fragment of the structure shown in Fig. 1 as seen on the line 2—2 of Fig. 1; Fig. 3 is a top plan view of a fragment of the structure shown in Fig. 1 as seen upon the line 3—3 of Fig. 1; Fig. 4 is a vertical section through a bottom of the derrick with parts of the outfit being omitted to better show the invention; Fig. 5 is an enlarged section as seen on the line 5—5 of Fig. 4; Fig. 6 is a plan of the computing assembly at the floor of the derrick; Fig. 7 is a section as seen upon the line 7—7 of Fig. 6; Fig. 8 is a front elevation of the assembly shown in Fig. 6; Fig. 9 is a section as seen on the line 9—9 of Fig. 8; Fig. 10 is a section as seen on the line 10—10 of Fig. 8; Fig. 11 is a section as seen upon the line 11—11 of Fig. 10; and Fig. 12 is a diagrammatic elevation of the complete rig. 75

In the drawings, a rotary rig has been shown and the details thereof other than the computing assembly, the gearing from a crown sheave to the assembly, the mounting for the rotary table, the computing assembly and the controls therefor are shown for illustrative purposes only. The invention is not limited to a particular type of well drilling outfit. The derrick indicated by 15 has mounted at the top thereof a crown sheave block, having assembled thereon sheaves, one of which indicated by 16 has a line such as 85 cable 17 passed thereover, and it is the revolution of the sheave 16 which controls the upward and downward movement of any ap- 90 95

paratus being run into the hole, and it is such revolutions of a sheave such as 16 which are to be measured in the embodiment of the invention herein shown. The sheave 16 is fixed to 5 rotate with the shaft 18 mounted in suitable bearings. If the sheave was mounted to rotate on the shaft, means other than the one herein described may be provided driving the line to be measured. An extension of the 10 shaft indicated by 18 is provided with a smaller pulley 19, having a gang of sheave grooves thereon. At one side of the derrick is a frame 14 having journalled thereon corresponding sheaves 20 and 21. A cable 22 15 constituting a belt is passed over pulley 21, passing to pulley 19, around which it is semi-circularly wrapped and then passing to and over pulley 20, then passing to and over pulley 19 and so continued until three or more 20 lines of said cable pass and encircle pulley 20 and four lines or more of said cable pass and encircle pulley 19 and two lines of said cable pass and encircle pulley 21. The wrapping is for the purpose of preventing over-winding 25 of the cable and for preventing slippage. The leads of the cable pass downward toward the floor of the derrick. These leads are indicated by 22^a and 22^b respectively.

Mounted upon the floor of the derrick or 30 in any other suitable position is a base 23 to which are secured bearing standards 24 and 25 having bearing blocks in which are journalled shafts 26 and 27. Mounted upon shaft 26 is a gang sheave 28, and mounted upon 35 shaft 27 is a similar gang sheave 29. The cable 22 is passed around sheaves 28 and 29. Thus, upon rotation of the crown sheave 16, the sheaves in the computing apparatus will be caused to rotate.

40 Fixed to the end of shaft 27 is a hub 30 so arranged as to be rotated with the shaft. The hub is provided with a flange to which is bolted a friction disk wheel 31. Bearing standards 32 and 33 carry bearing blocks, in 45 which is journalled a shaft 34 having a screw thread. Secured to the end of shaft 34 is a crank handle 35 for rotating the shaft. Mounted upon the shaft 34 is a lever frame 36. This frame is provided with an enlargement 50 at the center in which is a female thread meshing with the thread on shaft 34. The frame 36 is free to be moved axially on the shaft so that upon rotation of the shaft 34, the frame will be moved longitudinally of the 55 shaft. Mounted upon the upper end of the frame 36 is computing or recording mechanism 37. This mechanism may be of the character well known in the art of computing machines and registers revolutions which may be 60 translated into terms of lineal distance. The particular construction of this computing mechanism is not material to the present invention except that it will register and record an amount proportionate to the revolution of 65 its shaft indicated by 38, and may accumulate

movement in one direction or total that in both as desired. It is to be understood that by accumulator is meant any device which will record travel and is inclusive of devices which mark on charts the amount of hole 70 drilled. Fixed to the shaft 38 is a friction wheel 39 arranged to be engaged with the friction drive wheel 31. The frame 36 is mounted to rock upon the shaft 34 so that the driven wheel 39 may be moved into and 75 out of engagement with friction wheel 31. It is obvious that the counter, or computing device, may be made to record the revolutions made by sheave 16 and in so doing it is arranged to read in the distance of the travel of 80 any apparatus being run into the hole, since such travel and distance is a function of the number of revolutions made by sheave 16. To properly adjust the apparatus the friction wheel 39 may be moved by the shaft 34. 85 This is done by test.

Extending along the base plate 23 below the shaft 34 and parallel thereto is a rail 40. Spaced therefrom and parallel to rail 40 is a fixed rail 41. The foot of the lower leg of 90 frame 36 is disposed between the rails. A threaded pin 42 is disposed in leg 36 for engagement of one end with the rail 40. Secured to the leg 36 below pin 42 is a bowed leaf spring 43, the ends of which engage and 95 press against rail 41. The construction is such that the spring 43 tends to maintain the frame 36 in such position that friction wheel 39 will be in engagement with the friction disk 31. However, the frame may be swung 100 toward rail 41 against the action of the spring and the friction wheel 39 and positioned out of engagement with the friction disk. The friction wheel and the friction disk comprise a set of adjustable transmission ratio gears 105 which may be connected and disconnected by swinging of the frame 36. Rail 40 is mounted to rock having trunnions at its ends mounted in bearing blocks 44 secured to the base plate 23. This permits the rail 40 to be 110 swung and thereby move the frame 36 by reason of engagement of the pin 42 with the rail. An ear 45 is formed on one end of rail 40 and has a hole through which extends the shank of a link rod 46. The end of this 115 rod has an eye and is joined by a link with an eye 47. Eye 47 is secured to a cylinder 48. Slidably mounted in the cylinder is a washer 49 secured to a rod 50. Rod 50 extends to a bell crank 51, see Fig. 4. In Fig. 4 the computing mechanism structure is indicated generally by A. The other arm of the bellcrank lever 51 is secured to a link rod 52 which is attached to an arm of a bellcrank lever 53. A link rod 54 connects bellcrank lever 53 to 120 a bellcrank lever 55 disposed with one arm below the center of a leaf spring 56. Leaf spring 56 is semi-elliptic having shackles 57 (see Figs. 4 and 5) at the ends secured to derrick sills 58 supporting a rotary table. 125 130

The sills 58 are cut away to accommodate beams 60 supporting the rotary table 61. A clearance is provided between the bottoms of the beams 60 and the sills 58 so as to permit a limited movement, up and down rocking movement of the rotary table. The spring 56 normally maintains the table at one end in its upper position. Upon weight being placed upon the table, it will deflect downwardly, rocking the bellcrank 55 and causing rocking of the bellcrank 51 and a pull upon the rod 50. Between the end of the cylinder 48 and the washer 49 is a compression spring 62. This is of sufficient strength so that the cylinder will normally be moved by pull upon rod 50 and motion transmitted to the rod 46, thereby rocking the rail 40. This will cause the frame 36 to be swung so that the friction wheel 39 is disposed out of engagement with the friction disc 31. Thus, an actuating means is provided so that if weight is placed upon the rotary table, the computing mechanism will be thrown out of operation. In the operation of the drilling rig, there are times in which easing and other parts are lowered through the rotary table. Slips are placed in position in the table holding the drill pipe or string. At such times it is undesirable to have the computing mechanism in operation, otherwise an error will be made in computing the revolution of sheave 16 and the consequent travel of the line or other applicances run in the hole, since the cable and the traveling block are then caused to move up and down during such operation, but not as a function of the distance of travel apparatus may be running into the hole. It is only when the slips are removed and string is lowered into the hole that the operation of the computing mechanism is desired.

However, during drilling operation, some strain may be placed upon the table tending to deflect it because of frictional engagement of the drill string or kelley with the table.

In order to avoid the computing mechanism being placed out of operation at such time, we have provided a lug 63 outstanding from one side of rail 40. Arranged to engage the lug is a hook 64 pivotally mounted upon a shaft 65 and having at the other end thereof a crank arm 66. The shaft 65 is journaled in the bearing standard 33. A tension spring 67 tends to hold the hook out of engagement with the lug 63 so as to release the latter.

Crank arm 66 is secured to a rod 68 which leads to a control lever 69 having a link 70. The control lever 69 is for the purpose of starting and stopping the operation of the rotary table. The link 68 is so connected that when the control lever is in the position to place the table in operation, rod 68 will be moved to position catch 64 so as to release the rail 40, and thereby place the latter in operation. When the control lever 69 is in position so that rotary table is out of operation, rod

68 will be moved to permit a catch 64 to hold the rail 40 against movement. Thus, a control means is provided so when the rotary table is in operation, the actuating means is retained against disconnecting the gear shaft and placing the computing mechanism out of operation. This control mechanism is shown diagrammatically and may be varied.

It is obvious that the comprising mechanism may be of a character such that there are two sets of figures, one of which will always record total depth attained and will not subtract or run back when operating tool upward. The other set of figures may record depth downward and will subtract or run back when operating the tool upward in the well.

In Fig. 12, a rotary drilling rig is shown. The derrick is indicated by B, the crown block assembly by C and the tackle block gear by D. The accumulator is marked A. E is the rotary engine and F the table. In such a rig, it may be found advisable to connect a line to the tackle block and measure its travel.

What we claim is:—

1. In combination with a rotary well drilling rig having a crown pulley, a line passing thereover for causing travel of apparatus into the well hole, a device for causing rotation of the drill string; a computing mechanism for recording the lineal travel of said apparatus, gearing connecting said mechanism and said pulley including actuating means to connect and disconnect said computing mechanism from operation by said gearing; and means operated by movement of said device axially downward of said drill string to operate said actuating means to disconnect said computing mechanism.

2. In combination with a rotary well drilling rig having a crown pulley, a line passing thereover for causing travel of apparatus into the well hole, a device for causing rotation of a drill string; a computing mechanism for recording the lineal travel of said apparatus, gearing connecting said mechanism and said pulley including actuating means to connect and disconnect said computing mechanism from operation by said gearing, there being an adjustable gear ratio device included in said gearing; and means operated by movement of said device axially downward of said drill string to operate said actuating means to disconnect said computing mechanism.

3. In combination with a rotary well drilling rig having a crown pulley, a line passing thereover for causing travel of apparatus into the well hole, a device for causing rotation of a drill string, control means to place said device into and out of operation; a computing mechanism for recording the lineal travel of said apparatus, gearing connecting said mechanism and said pulley including actuating means to connect and disconnect said

- computing mechanism from operation by said gearing; means operated by movement of said device axially downward of said drill string to operate said actuating means to disconnect said computing means; and means associated with said control means and operated thereby to retain said actuating means in connected condition upon operation of said device.
4. In combination with a well drilling rig having a crown pulley and a line passing thereover for causing travel of apparatus into the well hole; measuring apparatus comprising a computing mechanism for recording the lineal travel of said apparatus, and gearing connecting said mechanism and said pulley including an adjustable friction driven wheel and a drive wheel.
5. In combination with a rotary well drilling rig having a crown pulley, a line passing thereover for causing travel of apparatus into the well hole, a device for causing rotation of a drill string, control means to place said device into and out of operation; a computing mechanism for recording the lineal travel of said apparatus, gearing connecting said mechanism and said pulley including actuating means to connect and disconnect said computing mechanism from operation by said gearing, there being adjustable friction driven and drive wheels included in said gearing; and means operated by movement of said device axially downward of said drill to operate said actuating means to disconnect said computing mechanism.
6. In combination with a rotary well drilling rig having a crown pulley, a line passing thereover for causing travel of apparatus into the well hole, a device for causing rotation of a drill string, control means to place said device into and out of operation; a computing mechanism for recording the lineal travel of said apparatus, gearing connecting said mechanism and said pulley including actuating means to connect and disconnect said computing mechanism from operation by said gearing; an adjustable gear ratio device included in said gearing; means operated by movement of said device axially downward of said drill string to operate said actuating means to disconnect said computing means; and means associated with said control means and operated thereby to retain said actuating means in connected condition upon operation of said device.
7. In combination with a rotary well drilling rig having a crown pulley, a line passing thereover for causing travel of apparatus into the well hole, a device for causing rotation of a drill string, control means to place said device into and out of operation; a computing mechanism for recording the lineal travel of said apparatus, gearing connecting said mechanism and said pulley including actuating means to connect and disconnect said comput-
- ing mechanism from operation by said gearing, there being adjustable friction driven and drive wheels included in said gearing; means operated by movement of said device axially downward of said drill string to operate said actuating means to disconnect said computing means; and means associated with said control means and operated thereby to retain said actuating means in said connected condition upon operation of said device.
8. In combination with a well drilling rig having a crown pulley and a line passing thereover for causing travel of apparatus into the well hole; a measuring apparatus comprising a drive pulley geared to said crown pulley so as to be rotated thereby, a driven pulley, a belt gearing said drive and driven pulleys together, and computing mechanism for recording the lineal travel of said apparatus geared to said driven pulley.
9. In combination with a well drilling rig having a crown pulley and a line passing thereover for causing travel of apparatus into the well hole; measuring apparatus comprising a drive pulley geared to said crown pulley so as to be rotated thereby, a driven pulley, a belt gearing said drive to said driven pulley, a computing mechanism for recording the lineal travel of said apparatus, and an adjustable gear ratio set connecting said computing mechanism and said driven pulley.
10. In combination with a well drilling rig having a crown pulley and a line passing thereover for causing travel of apparatus into the well hole; measuring apparatus comprising a drive pulley connected to said crown pulley so as to be rotated thereby, a driven pulley, a belt gearing said drive to said driven pulley, a computing mechanism for recording the lineal travel of said apparatus, adjustable friction drive and driven wheels connecting said computing mechanism and said driven pulley.
11. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive and driven pulleys together, a computing mechanism for recording the lineal travel of said apparatus, a set of gears arranged to be thrown into and out of engagement for connecting said driven pulley and said computing mechanism whereby to place said computing mechanism into and out of operation; and means operated by movement of said device axially downward of said drill string to operate said gear set to disconnect said computing mechanism therefrom.
12. In combination with a rotary well drilling rig having a crown pulley, a line passing thereover for causing travel of apparatus

- into the well hole, a device for causing rotation of a drill string, control means to place said device into and out of operation; a drive pulley connected to said crown pulley 5 so as to be rotated thereby, a driven pulley, a belt gearing said drive pulley to said driven pulley, a computing mechanism for recording the lineal travel of said apparatus, a set of gears arranged to be thrown into and out 10 of engagement for connecting said driven pulley and said computing mechanism whereby to place said computing mechanism into and out of operation; means operated by movement of said device axially downward 15 of said drill string to operate said gear set to disconnect said computing means; and means associated with said control means and operated thereby to retain said actuating means in connected condition upon operation of said 20 device.
13. In combination with a rotary well drilling rig having a crown pulley, a line passing thereover for causing travel of apparatus into the well hole, a device for causing rotation of a drill string; a drive pulley 25 connected to said crown pulley so as to be rotated thereby, a driven pulley, a belt gearing said driven pulley to said drive pulley, a computing mechanism for recording the lineal travel of said apparatus, a set of adjustable ratio gears arranged to be thrown into and out of engagement for connecting said driven pulley and said computing mechanism whereby to place said computing mechanism 30 into and out of operation; and means operated by movement of said device axially downward of said drill string to operate said set of gears to disconnect said computing mechanism therefrom.
14. In combination with a rotary well drilling rig having a crown pulley, a line passing thereover for causing travel of apparatus into the well hole, a device for causing rotation of a drill string, control means 45 to place said device into and out of operation; a drive pulley connected to said crown pulley so as to be rotated thereby, a driven pulley, a belt gearing said drive pulley to said driven pulley, a computing mechanism for recording the lineal travel of said apparatus, a set of adjustable ratio gears arranged to be thrown into and out of engagement for connecting said driven pulley and said computing mechanism whereby to place said computing mechanism into and out of operation; means operated by movement of said device axially downward of said drill string to operate said set of gears to disconnect said computing mechanism therefrom; and means associated with said control means and operated thereby to retain said actuating means in connected condition upon operation of said device.
15. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive pulley to said driven pulley, a computing mechanism for recording the lineal travel of said apparatus, 50 a rotary table for causing rotation of the drill string, control means to place said table into and out of operation; a computing mechanism for recording the lineal travel of said apparatus, gearing connecting said mechanism and said pulley including actuating means to connect and disconnect said computing mechanism from operation by said gearing; and means operated by downward movement of said table 55 to operate said control means to disconnect said computing mechanism.
16. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive pulley to said driven pulley, a computing mechanism for recording the lineal travel of said apparatus, adjustable friction drive and driven wheels for connection of said computing mechanism and said driven pulley, one of said discs being movable into and out of driving engagement with the other whereby to connect and disconnect said computing mechanism therefrom; and means operated by movement of said device axially downward of said drill string to operate said friction wheels to disconnect said computing mechanism therefrom.
17. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive pulley to said driven pulley, a computing mechanism for recording the lineal travel of said apparatus, adjustable friction drive and driven wheels for connection of said computing mechanism and said driven pulleys, one of said wheels being movable into and out of driving engagement with the other whereby to connect and disconnect said computing mechanism therefrom; means operated by movement of said device axially downward of said drill string to operate said friction wheels to disconnect said computing means therefrom; and means associated with said control means and operated thereby to retain said actuating means in connected condition upon operation of said device.
18. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive pulley to said driven pulley, a computing mechanism for recording the lineal travel of said apparatus, 100 a rotary table for causing rotation of the drill string, control means to place said table into and out of operation; a computing mechanism for recording the lineal travel of said apparatus, gearing connecting said mechanism and said pulley including actuating means to connect and disconnect said computing mechanism from operation by said gearing; and means operated by downward movement of said table to operate said control means to disconnect said computing mechanism.
19. In combination with a rotary well drilling rig having a crown pulley, a line passing thereover for causing travel of apparatus into the well hole, a device for causing rotation of a drill string, control means to place said device into and out of operation; a drive pulley connected to said crown pulley so as to be rotated thereby, a driven pulley, a belt gearing said drive pulley to said driven pulley, a computing mechanism for recording the lineal travel of said apparatus, 105 a rotary table for causing rotation of the drill string, control means to place said table into and out of operation; a computing mechanism for recording the lineal travel of said apparatus, adjustable friction drive and driven wheels for connection of said computing mechanism and said driven pulley, one of said discs being movable into and out of driving engagement with the other whereby to connect and disconnect said computing mechanism therefrom; and means operated by movement of said device axially downward of said drill string to operate said friction wheels to disconnect said computing mechanism therefrom.

gearing connecting said mechanism and said pulley including actuating means to connect and disconnect said computing mechanism for operation by said gearing, there being an 5 adjustable gear ratio device included in said gearing; and means operated by downward movement of said table to operate said actu-

ating means to disconnect said computing mechanism therefrom.

In witness that we claim the foregoing we 10 have hereunto subscribed our names this 30th day of November, 1927.

WILFRED H. GEIS.

JAY EMERY VAN GUNDY.
